UNITED STATES PATENT OFFICE.

LUCIUS V. WALKLEY, OF PLANTSVILLE, CONNECTICUT.

SCREW DRIVER.

Application filed December 27, 1926. Serial No. 157,132.

This invention relates to screw drivers, and particularly to improvements in the structure of the handle or the portion adjacent the handle of the tool, whereby the 5 operator will be enabled to obtain a firmer and more comfortable grip thereon, so that not only can he apply a more forceful turning movement thereto, but also there will be less tendency for the tool to slip in his 10 hand when in use. In addition, owing to the fact that a turning force may be applied to the tool even when not gripped rigidly by the hand of the operator, a less tiresome effort is required in its use and the fingers 15 of the hand grasping the tool are not so likely to become tired and cramped.

One object of the invention is the provision of a screw driver or similar tool, having a portion adjacent the handle of suitable 20 configuration to receive the fingers of the operator when the tool is in use.

A further object of the invention is the provision of a screw driver or similar tool, having an improved grip portion whereby 25 it may be grasped firmly and operated with a minimum of effort.

A still further object of the invention is the provision of a screw driver, having adjacent the handle end thereof, flattened de- 30 pressions to receive the thumb or forefinger or both of the operator to enable the latter to obtain a firm grasp upon the tool and to apply a turning motion thereto with a minimum expenditure of effort.

35 A further object of the invention is to provide a screw driver having a shank portion and a relatively short handle portion, and depressed flattened surfaces between the shank portion and handle portion to receive 40 the thumb and fingers of the operator for the purpose described.

To these and other ends the invention consists in the novel features and combinations of parts to be hereinafter described and 45 claimed.

In the accompanying drawings:

Fig. 1 is a top plan view of a screw driver, embodying my invention;

Fig. 2 is a side view of the same.

50 The improved screw driver which I have illustrated and described as embodying a preferred form of my invention, comprises a structure wherein the main portion consists of a one-piece forging or stamping 55 which extends the entire length of the tool and is shaped to form a bit 10, a shank 11,

which is gradually increased in cross section at its upper end to provide a conoidal bolster 12, and a flattened web portion 13, to which are applied the handle scales 14 and 15, the latter being usually made of wood. At each end of the web portions 13 are provided shoulders 16 and 17, between which the handle scales lie, the two upper shoulders 16 being continued to form a relatively broad butt 18. The handle scales may be secured in place by any suitable means, such as the rivets 19. It will be, of course, understood that in its broader aspects the invention is not confined to a tool having the 70 particular features above described, these being shown as illustrative rather than definitive of the invention.

It will be noted that in the form of my invention illustrated in the drawings, the conoidal bolster 12 is located at some distance below the shoulders 17, adjacent the handle scales, and between the bolster and these shoulders the body of the tool is dished out and flattened to provide relatively broad flat 80 depressions or valleys 20 and 21, on opposite sides of the tool, which depressions are separated by a relatively thin web and have gradually inclined or rounded surfaces 22 and 23 merging into the bolster below and 85 the shoulders of the handle portion above.

Referring to Fig. 1, it will be seen that these dished out portions or depressions are relatively broad. In fact, as shown in this figure, the body portion of the tool at this 90 point is broader than at the adjacent points, above and below, so as to give a relatively flat broad seat or rest to receive the thumb or finger of the operator. Referring to Fig. 2, it will also be obvious that while the 95 body portion of the tool has been considerably widened at this point, the thickness is reduced so that inclined or rounded surfaces are provided between the intermediate part of the depression and the bolster and handle portion of the tool. These inclined or rounded portions will tend to keep the thumb and finger of the operator in the proper position on the tool and prevent the handle slipping longitudinally relatively to the operator's hand. At the same time, a broad surface is furnished against which pressure may be applied to give the tool a 105 turning motion on its longitudinal axis.

In the form of my invention which is 110 illustrated in the drawings, the handle of the tool or that part upon which the handle

scales are secured, is somewhat shorter than usually provided in tools of this character, owing to the fact that the upper end of the thumb and the forefinger are received against the surfaces 20 and 21, and therefore, the handle scales do not have to be of sufficient length to accommodate the entire hand of the operator.

The general shape of the tool has, however, been preserved, as the handle portion thereof is of oval shape so as to properly fit the hand and tapers downwardly from a point adjacent the butt of the tool toward the bolster. The valleys or dished out portions are so formed that the fingers will assume a natural position against the broad flattened surfaces there provided, so that the tool may be held in the hand and a turning force applied thereto with little effort. That is to say, it will not be necessary to trip the handle so rigidly as is necessary in the use of tools of this character having a plain, round or oval handle without the flattened surfaces.

While I have shown and described a preferred embodiment of my invention, it will be obvious that it is not limited to all the details shown, but is capable of modification and variation within the spirit of the invention and within the scope of the appended claims.

What I claim is:

1. A screw driver having a body portion formed to provide a bit, a shank, and a handle, and having adjacent the lower end of the handle and extending across the screw driver a relatively broad flattened surface to receive the finger of the operator.
2. A screw driver having a body portion formed to provide a bit, a shank, and a handle, and having adjacent the lower end of the handle a relatively broad flattened surface to receive the finger of the operator, and a shoulder below the broadened surface.
3. A screw driver comprising a handle structure and a bit supporting shank connected together by means of an intermediate

bolster structure, said bolster structure being provided with a relatively broad flattened surface adjacent the handle portion and between it and the shank.

4. A screw driver comprising a handle structure and a bit supporting shank connected together by means of an intermediate bolster structure, said bolster structure being provided with a depression to receive the finger of the operator, and a shoulder below the depression.

5. A screw driver comprising a handle structure and a bit supporting shank connected together by means of an intermediate bolster structure, the said bolster structure being provided with a transverse valley to receive the finger of the operator and providing a flattened web portion between the handle and the shank.

6. A screw driver comprising a handle structure and a bit supporting shank connected together by means of a bolster structure, the bolster structure being provided with a relatively thin flat web portion to receive the finger of the operator, and inclined shoulders above and below said web portion, by which the said portion merges into the handle and bolster.

7. As a new article of manufacture the herein described screw driver consisting of the blade, the round shank, bolster, handle web and butt, all formed in one piece and handle scales secured to said handle and web, the handle portion being elliptical in cross-section for the most part and between it and the bolster being concave and widened on both sides of the handle to receive the ball of the thumb and the joint of the forefinger, thus providing for a firm grasp and a rigid control against turning, while the hand may apply end pressure by the pressure of the finger and thumb upon the shank of the tool.

In witness whereof, I have hereunto set my hand this 23d day of December, 1926.

LUCIUS V. WALKLEY.
